UNITED STATES PATENT OFFICE

LARS R. JORGENSEN, OF BERKELEY, CALIFORNIA

ARCH DAM

Application filed May 28, 1929. Serial No. 366,578.

This invention relates to improvements in dams, and more especially to concrete dams of the constant angle arch type.

In the design of this type of dam there is a tendency to produce an overhang at the abutments, particularly at the lower elevations. For economical reasons the angles subtended by the arch should be kept as constant and as near to 120° as possible, as has been fully disclosed and described in my former Patent Number 986,718. This is easily accomplished in a U-shaped canyon, but it is seldom possible in a pronounced V, or inverted A shaped canyon. Even where a considerable overhang is allowed at the abutments, the subtended angle will be found to decrease in value towards lower elevations, where the structure is designed to fit ordinary canyons. In other words, the arch becomes flatter towards the foundation, and therefore more inefficient.

For the purpose of explaining and describing the dam structure forming the subject matter of the present application, I refer to the dam as being divided horizontally into three zones; a top or upper zone; a middle zone; and a bottom zone.

The object of the present invention is to improve the shape of the arches of the several zones so as to increase strength, and at the same time reduce the amount of material required to a minimum. The invention more specifically stated consists in shaping the arches in the top zone at the abutments in such a manner as to obtain the roundest possible arch with a minimum of overhang. The arch is, in this manner, given an elliptical shape, flatter at the crown than at the abutments.

At and towards the top the arches are to be designed as three centered arches or the like, in a horizontal plane, with the shorter radius curves at the abutments.

In the so-called middle zone the arch may be designed as an ordinary arch except that it is made thicker at the abutments than at the crown. In the bottom zone the arch may be designed as an ordinary arch except at and towards the foundation, where the arch is made thicker at the crown than at the abutments to take care of the larger amount of

shear ordinarily present in this part of the structure. Should the span at the bottom be rather long, it is possible to keep a large subtended angle, thereby enabling a large proportion of the load to be taken by actual arch action. In that case the upstream face is brought upstream at the abutments by means of a short tangent or reverse curve. This will cause any possible overhang to be filled out, and furthermore enables the abutments to take better care of bending stresses.

In order to still further increase the size of the subtended angle, or maintain it at a larger value towards lower elevations, the top zone of the dam is given a slope in a downstream direction in such a manner that the central part of the dam at and near the crest overhangs the middle zone on the downstream side. The downstream face of the middle zone will, in that instance, be made substantially vertical, and the downstream face of the bottom zone will slope in a downstream direction towards lower elevations in the usual manner.

By constructing arch dams in most V, or inverted A-shaped canyons, as explained above, the length of the upstream radius at different lower elevations can be made to decrease towards the bottom at a greater rate than has been made possible heretofore, assuming, of course, that a reasonable amount of overhang will be used at the abutments in both cases. Since the thickness of the arch is proportional to the upstream radius, the importance of decreasing the length of the upstream radius should at once be apparent.

The dam structure is shown by way of illustration in the accompanying drawings, in which:

Fig. 1 is a plan view of the dam,

Fig. 2 is a vertical cross section of the dam taken on line II—II, Fig. 1,

Fig. 3 is a plan view of the top zone of the dam,

Fig. 4 is a plan view of the middle zone of the dam,

Fig. 5 is a plan view of the lower zone of the dam as it would appear in a narrow canyon,

Fig. 6 is a plan view of the lower or bottom zone showing a modification of the up-

stream face to avoid the overhang and to increase the thickness of the abutments so as to resist bending where the canyon is wide at the bottom.

- 5 For the purpose of description it will here be stated that the dam and the dam site illustrated are merely imaginary. It will also be stated that the dam must be considered as being divided horizontally into three superposed zones, to wit, a top zone, a middle zone and a bottom zone. The division of the body of the dam into the zones specified is an arbitrary one for the sake of clearness. The imaginary dam illustrated in this instance is one hundred and fifty feet high, and each of the three zones are shown as fifty feet in height. For an actual dam which has to fit a rough canyon no such regularity is possible.
- 20 When the design of such a dam is commenced, the procedure is from the crest and downward.

The top contours are here indicated at O—O, and the top arch is laid out to subtend an angle of say 120° . The arch is, however, not carried clear to the abutments with one radius but shorter radii are used at the abutments, which brings the arch further back in a downstream direction at the abutments than otherwise. This is indicated in Fig. 3 by dotted lines $a—a$ which represents a continuation of the arch as laid out for the central portion.

The arch at contours 10 and 20 is laid out in the same manner only the arch is "bent back" at the abutments a less amount towards lower elevations. At elevation 40 there is nothing gained in bending the arch back for this imaginary site and, therefore, it is not done at this elevation, but the maximum allowable overhang is maintained if necessary for economy's sake.

An overhang of three to four feet at the abutments is generally considered good practice. The arch butting into the abutment at elevation 10 has about that amount of overhang, as indicated at b , but it is plainly seen from Fig. 3 that if the ends of the arch at elevation O had not been bent in a downstream direction the overhang C would have been nearly twice as large.

The more overhang one is willing to take, the shorter the upstream radii can be made at lower elevations and, therefore economy, as far as concrete is concerned, is kept high. More than a certain overhang cannot be tolerated structurally, but it is seen that by bending the arches back at the abutments near the crest the benefit of nearly double the allowable overhang may be obtained lower down, besides the line of pressure in such an arch will more nearly coincide with the centerline of the arch than it would in a perfectly circular arch.

65 An actual canyon may be shaped such that

this scheme can be used at lower elevations also to diminish the length of the upstream radii at lower elevations. At the same time the "bending back" of the arch at the abutments has a tendency to relieve the bending stresses in the arch at the abutments, where they are the highest.

Fig. 3 shows a considerable overhang of the dam near the center above the river, as indicated at B. Another view of this same overhang is shown in Fig. 2. The purpose of this overhang is the same as that of "bending back" the arch at the abutments, namely, to be able to still further shorten the upstream radii at lower elevations. It is seen, that each lower arch slice is so to speak pushed upstream in relation to any other arch above, thus enabling a rounder arch to be inscribed without increasing the amount of overhang at the abutments above that assumed as allowable.

70 In Fig. 4 the so-called middle zone of the dam is shown. In a narrow canyon overhang on the upstream face at the abutments would most likely not be used, whereas, for a dam in a wide canyon it would be used. The downstream face of the dam may either be struck from a center located upstream of the center for the corresponding upstream face in which case the thickness of the arch would be gradually increased from crown to abutment, or the same center for up and downstream faces may be used with some additional material placed at and near the abutments to increase 80 the thickness where it is most necessary.

75 In Fig. 5 the lower zone is shown. This represents a fairly narrow canyon in which overhang on the upstream side at the abutments can seldom be used to advantage in a commercial design. The arch is thick with 90 relation to its length and acts more like a beam. The downstream face at and below contour 110 is struck from one center as indicated at Fig. 5. This makes the arch below 95 contour 110 thicker at and near its central portion. This extra material is active in resisting the horizontal bending moment in the arch, the possible vertical bending moment in the cantilever besides the cantilever shear.

100 In Fig. 6 the same lower zone of the dam is shown, but in a wide canyon. What would otherwise be a considerable overhang is filled out with material (concrete) to a tangent or reverse curve, such as shown at f . The material added increases the thickness of the abutments. The arch action is more effective in the wider canyon than in the narrow one shown in Fig. 5, and therefore it is logical to increase the thickness at the abutments either 105 on the upstream side or downstream side, or on both sides.

110 At the very bottom the center for the downstream face may be located in a downstream direction with relation to the center for the 115

upstream face, the same as shown in Fig. 5, this is a matter of design.

Having thus described my invention, what I claim and desire to secure by Letters Patent is:

5. 1. In a constant angle arch dam which is divided horizontally into a bottom, a middle and a top zone, and where said zones are superposed the top zone having the ends of the arches of sharper curvature towards the abutments than the central part of the arches, the central part of said arches projecting partly outside the middle zone on the downstream side, the amount of projection being 10 maximum at the crown of the arch and diminishing to zero towards the haunches and towards lower elevations.
15. 2. In a constant angle arch dam which is divided horizontally into a bottom, a middle and a top zone, where said zones are superposed the top zone having the ends of the arches of sharper curvature towards the abutments than the central part of the arches, the central part of said arches projecting partly 20 outside the middle zone on the downstream side, the amount of projection being maximum at the crown of the arch and diminishing to zero towards the haunches and towards lower elevations, the middle zone presenting 25 a substantially vertical face on the downstream side in the center, and having faces consisting of substantially circular arches which are substantially concentric and uniform in thickness from the center to the abutments, the lower zone having substantially circular arches with additional material placed on the upstream side at and towards the abutments.
30. 3. In a constant angle arch dam which is divided horizontally into a bottom, a middle and a top zone, where said zones are superposed the top zone having the ends of the arches of sharper curvature towards the abutments than the central part of the arches, 35 the top zone of the dam projecting partly outside the middle zone on the downstream side, the amount of projection being a maximum at the crown of the arch and diminishing to zero and towards lower elevations, the middle zone being substantially vertical on the downstream side in the center and having faces consisting of substantially circular arches which are substantially concentric and uniform in thickness from the center to 40 the abutments.
45. 4. In a constant angle arch dam which is divided horizontally into a bottom, a middle and a top zone, where said zones are superposed the top zone having the ends of the arches of sharper curvature towards the abutments than the central part of the arches, the top zone of the dam projecting partly outside the middle zone on the downstream side, the amount of projection being a maximum at the crown of the arch and diminishing 50 to zero and towards lower elevations, the middle zone being substantially vertical on the downstream side in the center and having faces consisting of substantially circular arches which are substantially concentric and uniform in thickness from the center to 55 the abutments.
55. 5. An arch dam having the central part of the arch leaning in a downstream direction, and the end portions of the arch leaning in an upstream direction.
60. 6. A constant angle arch dam having the central part of the arch leaning in a downstream direction, and the end portions of the arch leaning in an upstream direction, the up and downstream faces forming warped surfaces both in vertical and horizontal planes.
65. 7. In a constant angle arch dam which is divided horizontally into a bottom, a middle and a top zone and where said zones are superposed, the center part of the upper zone of the arch having an overhang leaning in a downstream direction and end portions of the upper zone of the arch having an overhang leaning in an upstream direction.
